UNITED STATES PATENT OFFICE.

LEWIS T. HOUGHTON, OF WORCESTER, MASSACHUSETTS.

YARN-TENSION DEVICE.

Application filed March 2, 1920. Serial No. 362,866.

To all whom it may concern:

Be it known that I, Lewis T. Houghton, a citizen of the United States, residing at Worcester, in the county of Worcester and 5 State of Massachusetts, have invented a new and useful Yarn-Tension Device, of which the following is a specification.

The principal objects of this invention are to secure an even tension on the yarn in 10 a spooler or the like by providing substantially the same resistance irrespective of the speed of the yarn and of the difficulties which it encounters in being drawn off the cop or bobbin on which it is wound, to 15 cheapen the construction, to eliminate all springs, to make it easy and practical to obtain a uniform tension, and especially to provide a tension which will operate uniformly and satisfactorily at excessive speeds. 20 To do this I compensate for any change in yarn speed or resistance by changing the distance apart of the yarn guides and I further provide a compensating weight for neutralizing any change in effective weight of 25 the movable guides and associated parts due to change in position.

The invention also involves improvements in the yarn guide which directs the yarn to the guides.

30 Further objects and advantages of the invention will appear hereinafter.

Reference is to be had to the accompanying drawings, in which

Fig. 1 is an end view of a part of a spooling machine with a preferred embodiment of 35 this invention applied thereto and shown in its normal position;

Fig. 2 is a front view of the same looking in the direction of the arrow 2 in Fig. 1 40 showing one of the tensioning elements, and

Fig. 3 is a plan as indicated by the arrow 3 in Fig. 2.

The yarn in spooling is subjected to many changes in strain owing to the changes in 45 diameter of the spool and of the bobbin or yarn packages that are being spooled, especially in spooling filling-wound bobbins, where the speed of the uncoiling is very quickly increased 300% and as quickly decreased, the diameter of the yarn package varying from $\frac{1}{2}$ an inch to $1\frac{1}{2}$ inches.

The tension is adjusted to the desired spool speed and the automatic decrease in tensioning distance between the tension fin-

gers or guides overcomes the increase in 55 yarn strain and provides a substantially uniform tension. The frictional path of the yarn through the guides is decreased as the yarn strain increases, and the quadrantly weighted pivoted guides provide a constant 60 uniform weight on the yarn, regardless of their changing pivotal position, thus providing a substantially uniform tension of the 65 yarn during the process of spooling. The mechanical structure may be varied to suit 70 the work that is required without change in the object of this invention.

The invention, although capable of general use, is shown as applied to the drawing 75 of yarn from a cop 10 to a spool 11. The mechanism for rotating the spool is not shown herein as it forms no part of this invention, but the spooler is provided with the usual longitudinal traverse rod 12 which is designed to support a series of spooler 75 guides 32 and corresponding tensioning devices. A supporting element for one of the cops and its tension device is shown as comprising a metal strip 14 passing over and resting on the rod 12. Its lower ends are 80 connected and pressed toward each other by a bolt 15, which also connects it with and supports a depending upright 16 formed of sheet metal. This is provided with a slot 17 through which passes a bolt fastened 85 by a nut 18 to give vertical adjustment to a horizontal supporting plate 19 which carries a sheet metal support 20 for a dead spindle on which the cop 10 or bobbin is supported 90 in vertical position.

On the strip 14 is a depending vertical sheet metal support 21 located in stationary 95 position and carrying a series of thread guides, in this instance comprising two fixed horizontal rods 22. Below this it carries a metal plate 23 which is provided with a slot 33 and is adjusted up and down by means of a bolt 34 in this slot. It also has two parallel transverse perforated ears 24 furnishing bearings for a shaft 25. Fixed 100 with respect to this shaft and swinging with it is a plate 26 which depends from the shaft and is provided with a pair of rigid tension fingers 27 projecting from the front of it with their outer ends extending downwardly. In normal position these fingers are substantially horizontal as shown in full lines in Fig. 2. The outer ends of the rods 105

22 are turned up to prevent the yarn running off the ends at high speed. The ends of the fingers 27 are turned down and back with an ogee curve to cause them to hold the yarn even when they move almost up to the position shown in dotted lines in Fig. 2.

The shaft 25 is provided beyond the front ear 24 with a comparatively heavy handle 28 for use in turning it. This extends substantially at right angles to the depending plate 26. These elements 26, 27 and 28 constitute a rigid unitary structure and are so proportioned that the swinging of the shaft 25, due to the varying lifting tension on the yarn, will not materially affect the weight which is exerted upon the yarn by this whole pivoted structure. In other words it will be observed that, as this pivoted structure is lifted, the moment about the shaft exerted by the fingers 27 and weight 28 decreases while the same motion increases correspondingly the moment of the plate 26. The increase in one compensates for the loss in the other and the combined weight dragging on the yarn tends to remain substantially constant, independently of the angular position of the fingers 27.

In this tension device, the amount of tension on the yarn depends on its speed and the vertical distance between the guides 22 and 27. This distance always depends on two factors, the vertical position of the whole structure carried by the plate 23, and the angular position of the parts carried by the shaft 25.

The maximum distance between the rods 22 and fingers 27, is made adjustable, as stated, to provide the normal tension desired for the kind of yarn to be wound, and the spool speed. Any increase in speed or resistance tending to increase the tension swings the fingers 27 up and decreases the tensioning space between the guides 22 and 27 and consequently tends to decrease the tension on the yarn. Thus, the normal tension is maintained without varying the weight on the guides 27.

The effective weight on the yarn of the pivoted guides, together with that of the handle 28 and plate 26 being substantially constant for all positions, this maintains the desired or normal tension. It is to overcome changes in tension, caused by variation in yarn velocity, that this structure is pivotally mounted. As these guides with the handle 28 extend substantially at right angles to the weight 26, they form substantially a quadrant, and whether this quadrant is formed by two weights at an angle to each other, or by a single member occupying the same total space, the amount of effective weight on the pivoted guides is made substantially constant regardless of their angular position. With a constant weight on the guides any increase in tension on the yarn

raises these pivoted guides, lessening the space between the guides, and thereby restoring the constant normal tension regardless of any increasing velocity of the yarn. This device makes it easy to obtain uniform and accurate adjustment. Further, if the adjustment of the plate 23 should not be quite correct, the automatic changing of the normal tensioning space compensates for it and restores the normal tension, regardless of changes in speed and the defects in the winding of the bobbins or cops. Any increase in tension is automatically taken care of, whether caused by increasing yarn speed or increase in resistance to the unwinding of yarn from the bobbin or cop. It will be noted that I use the weight of the pivoted guide fingers to produce tension and add to it by the use of the handle 28, which is really a weight, and then provide the compensating weight 26 for both. All these parts are held up by the yarn and exert some weight on it in all except the extreme position. None of them counterbalance the others to reduce the total effective weight.

In spooling, the spool speed is a large factor, providing and controlling the amount of tension. In practice, the velocity of the yarn increases nearly 300% while winding a spool on a common spooler, on account of the increasing diameter of the spool as the yarn is wound on it. To provide a normal tension for a changing velocity of the yarn, many arrangements of springs have been devised. In practice it has been found to be practically impossible to adjust these springs uniformly and when adjusted thus variation in temper and resistance as the springs are compressed or stretched, renders it impossible to maintain a uniform tension on the yarn. They have to be individually adjusted at frequent intervals with considerable expenditure of time. The present device eliminates all springs and their vexatious adjustments and cheapens the cost of manufacture.

Furthermore, the increase in yarn speed and consequent increase in tension between an empty spool and a full spool have caused great breakage of yarn. No other tension has successfully overcome this great trouble in spooling yarn. Many mills even use two spoolers with different spool speeds to overcome this great trouble. This difficulty is practically overcome by this invention.

In operation the yarn is guided through the extension device by means of an eye 31 formed on a rod 30 secured to the fixed plate 23 and extending around the end of the same. This eye is an open depression which is adapted to receive the yarn from the end and is located in proper position for guiding it to the thread guides at a point behind the angular front ends of the

same, and this with the open space provided underneath, prevents the yarn from ballooning against other parts of the device, thus further preventing many yarn breaks independent of the adjustment of the plate 23.

In threading the device, the swinging structure consisting of the parts 26, 27 and 28 is turned up to the position shown in dotted lines in Fig. 2. This is done by using 10 the arm 28 as a handle. Now the end of the yarn from the bobbin or cop 10 can be moved upwardly and, without shifting it back and forth to thread it, it will pass into the eye 31 and over the tops of the rods 22. There 15 is nothing in the way to hinder the placing of the yarn in position in this simple way.

After the yarn is laid on the rods the tension fingers are swung down from the dotted line position in Fig. 2, which brings the 20 yarn down between them as shown in that figure and Fig. 1.

In practice, this pivoted structure plays up and down with the variations in speed and resistance. The tension is found to be 25 so constant that a large percentage of the breaks is avoided and the winding is rendered comparatively uniform. This also permits the unwinding of the yarn in a true axial direction from a bobbin or cop below 30 for filling winding which has to be done as uniformly as possible. This has proved to be especially advantageous in practice because the speed can be greatly increased, thus increasing the output, and the normal 35 tension desired maintained even at great speeds. The breakage is reduced and the elasticity of the yarn preserved. It also greatly lessens the surfaces on which waste and lint can gather, and locates all such 40 surfaces where the lint cannot interfere with the proper operation of the device.

Although I have illustrated and described the invention as applied to a particular type of spooler and shown a specific form of the 45 mechanism I am aware of the fact that it can be applied to other types of winding machines and to the winding of thread, yarn, and cordage other than filling yarn, and that modifications can be made in the details of 50 construction without departing from the scope of the invention as expressed in the claims. Therefore I do not wish to be limited in these respects, but what I do claim 55 is:

1. A yarn tension device comprising two series of substantially horizontal guides for receiving and tensioning the yarn between them, one series being pivoted on a transverse axis, and means connected with them for 60 automatically keeping the total weight tending to hold down the pivoted guides substantially constant.

2. A yarn tension device comprising two series of thread guides, one series being pivoted on a substantially horizontal transverse 65

axis located near their ends and below the other series and having an arm and a weight both projecting from the vicinity of said axis and at substantially right angles to each other for keeping the total effective weight 70 substantially constant in different positions of said pivoted guides.

3. A yarn tension device comprising a series of fixed horizontal rods for supporting the yarn in horizontal position while threading, tension fingers alternating with said rods adapted to pass downwardly between them about a horizontal transverse pivot for providing the tension, and means for automatically applying a substantially constant 75 force to said fingers to hold them down, irrespective of their angular position within substantially a quadrant, said means acting to allow motion of the fingers up and down.

4. A yarn tension device comprising a 80 series of yarn guides, a parallel series of guides pivoted on a transverse axis and means for equalizing the effective weight tending to hold down the pivoted guides consisting of weights swinging with the 85 pivoted guides and all located substantially within and constituting the quadrant of a circle having the guide pivot as its center.

5. A springless yarn tension device comprising a series of fixed yarn guides located 90 in a substantially horizontal plane, a parallel series of weighted guides pivoted on a transverse horizontal axis at a distance below the fixed guides, and means for equalizing the effective weight tending to 95 hold down the pivoted guides consisting solely of a weight swinging with the pivoted guides and all located substantially within and constituting the quadrant of a circle having the guide pivot as its center. 100

6. In a yarn tension device, the combination with stationary yarn guide rods, of swinging yarn guide fingers cooperating therewith to guide the yarn, said swinging fingers being located in a position to act 110 by gravity to apply a tension to the yarn, additional means rigidly connected with said fingers for applying tension to the yarn, and a weight at an angle to said means and fingers, but swinging therewith, 115 in a position for further increasing the tension in inverse proportion to the effective weight of said means and fingers to compensate for any decrease in their effective weight due to their angular position. 120

7. A yarn tension device comprising a support, a vertical plate or flange projecting from it, guide rods parallel with the support and located on the plate, a pivoted set of horizontal guide fingers carried 125 under said rods by said support, a handle for operating the fingers projecting from the pivot in the same general direction as the fingers, and a compensating weight swinging with the fingers and handle but 130

depending from the pivot leaving an open space below said guides, and a yarn guide eye located below said guide rods and fingers whereby the ballooning of the yarn 5 is confined to said open space.

8. A yarn tension device comprising a support, a vertical plate or flange projecting from it, guide rods parallel with the support and located on the plate, a pivoted 10 set of guide fingers carried under said rods by said support, a handle for operating the fingers projecting from the pivot in the same general direction as the fingers, and a compensating weight swinging with the 15 fingers and handle but depending from the pivot.

9. In a yarn tension device, the combination with yarn guide rods, of swinging 20 yarn guide fingers located in a position to act by gravity to apply a tension to the yarn, and a weight at an angle to said fingers, but swinging therewith, located in position for further increasing the tension in inverse proportion to the effective weight of 25 said fingers.

10. A springless yarn tension device comprising a series of fixed yarn guides, a parallel series of guides pivoted on a transverse axis, means for equalizing the effective 30 weight tending to hold down the pivoted guides consisting of a weight swinging with the pivoted guides and located at a material angle thereto, and means for adjusting said two series of 35 guides toward and from each other to regulate the normal tension.

11. A yarn tension device comprising two 40 series of substantially horizontal guides for receiving and tensioning the yarn between them, one series being pivoted on a transverse axis, and means fixedly connected with them for automatically keeping the total weight tending to hold down the pivoted guides substantially constant, one

series of guides being adjustable as a whole 45 toward and from the other series.

12. In a yarn tension device, the combination of two series of thread guides for receiving and tensioning the yarn between them, one series of guides being pivoted, 50 whereby they can be turned back away from the other guides at the rear into a position substantially at right angles to the plane thereof, and two weights movable with the movable guides and extending in directions 55 substantially at right angles to each other from the pivot for counterbalancing each other and the movable guides.

13. A yarn tension device comprising rods for supporting the yarn while thread- 60 ing, pivoted tension fingers alternating with said rods adapted to pass between them for providing the tension, and means whereby said fingers are raised by the yarn passing under them and whereby the total weight 65 tending to hold them down will remain substantially constant.

14. In a yarn tension device, the combination with a series of horizontal rods for supporting the yarn, means for applying a substantially constant tension to the 70 yarn passing over said rods, and a rod located adjacent to the receiving side of the series of rods and provided with an open sided loop shaped eye on the side 75 away from said rods.

15. A compensating tension device comprising two relatively movable yarn guides, one having means for resisting any motion toward the other due to increase in yarn 80 tension, and means for compensating for any change in such resistance due to change in position, whereby the effective resistance will remain substantially constant.

In testimony whereof I have hereto affixed 85 my signature.

LEWIS T. HOUGHTON.
